UNITED STATES PATENT OFFICE

RANK H. KNEELAND, OF CHICAGO, ILLINOIS, ASSIGNOR TO SAFETY MINING COMPANY, OF CHICAGO, ILLINOIS, A CORPORATION

BLASTING CARTRIDGE

Application filed November 27, 1929. Serial No. 410,196.

This invention is concerned with blasting cartridges of the type wherein a compressed gas is employed as the blasting medium.

It is an object of the invention to simplify and thereby reduce the cost of construction and maintenance of blasting cartridges of the character indicated.

More particularly, it is an object of the invention to provide an improved and simplified means for the charging of such blasting cartridges.

Referring to the drawings,

Figure 1 is a view in longitudinal section illustrating an embodiment of the invention.

Figures 2 and 3 are enlarged fragmentary sectional views showing the two operative positions of the charging device.

The cartridge with which the present invention is associated consists generally of a cylindrical casing 1 which is internally hollowed out to provide a gas chamber 2, the open end of which is designed to be covered and sealed by a rupturable discharge disc 3. Secured adjacent the discharge disc 3 is a ring 4 formed of relatively hard steel, the function of which is to serve as an anvil or shear ring for the mild steel disc 3. This shear ring is forced into tight engagement with the disc 3 by means of a discharge cap 5, having threaded engagement with the end of the cartridge body. The gas chamber adjacent the opposite end of the cartridge is tapered toward the axial center line of the cartridge and at the center is bored out to receive an electrode 7, which extends a short distance into the gas chamber. The electrode is insulated from the body of the cartridge by means of an insulating member 8. The electrode 7 is formed as a portion of an enlarged sealing head 10, which is insulated from the body of the casing by means of an insulating disc 11. The disc 11 also serves the purpose of providing a seal between the member 10 and the adjacent wall of the cartridge, thus preventing the escape of gas from the chamber 2 around the electrode. A retaining and protecting disc 12 is screw threaded into the end of the cartridge body and bears against the outer surface of the member 10. This disc is adapted to be

screwed tightly in place by means of a pin wrench or the like, thus exerting pressure on the member 10 and effecting a secure seal between the member 10 and the cartridge body. It will be noted that member 10 and protector disc 12 are also separated by insulating member 13.

The cartridge as above described is designed to be charged with a compressed gas, the pressure of which may be increased to effect rupture of the disc 3 by means of a heater unit 18. This heater unit extends between and has electrical contact at its opposite ends with electrode 7 and rupturable disc 3 respectively and is of such construction as to be responsive to the passage of a relatively low electric current. In order to pass a suitable current through the heater unit, it is merely necessary to insert a contact plug through the opening 14 in the protector disc 12 and into the bore 16 provided therefor in the electrode. The other lead from a source of electricity may be connected directly to the body of the cartridge preferably by means of a wire passed through one or more apertures 17 formed therein. In the interest of safety, the opening 14 in the protector disc is normally closed by a pivoted cover plate 15, thus preventing the accidental engagement of the electrode with a source of electricity.

The present invention is more particularly concerned with the method and means whereby cartridges of this character may be charged with a compressed or liquefied gas. As herein shown this result is accomplished without the addition of a separate valve unit. Referring particularly to Figures 2 and 3 it will be observed that there is positioned between the rupturable disc 3 and the cartridge, a gasket 19 formed of fibre or any other suitable deformable material. It will also be noted that the sealing surface of the cartridge with which the disc 3 and the gasket 19 are designed to cooperate, is of stepped formation as indicated at 20 and 21. Thus, the initial pressure exerted upon the disc and the gasket by the discharge cap and shear ring serves to bring the gasket into sealing engagement with the step 20 of the sealing

surface formed on the cartridge. With the parts in this relative position, gas may be introduced by means of a suitable charging nozzle through the nozzle seat 23 and charging port 22, directly into the gas chamber 2. This is possible due to the fact that the gasket 19 is not in sealing engagement with the step 21 of the sealing surface. After the desired amount of gas has been charged into the cartridge, the discharge cap may be screwed further into the cartridge body, thus exerting an additional pressure on the disc 3 and gasket 19 and causing the gasket to be deformed in such a way as to effectively seal the entire area of the sealing surface formed on the cartridge and including both the steps 20 and 21. It will be apparent that after this has been done, the gas chamber is completely sealed against the escape of gas either around the discharge disc and through the discharge cap or through the charging orifice 22. It is quite well known that it is possible to cause fibre or the like to flow when subjected to high pressures and this is substantially what occurs when the discharge cap is screwed very tightly into the cartridge body. The gasket not only conforms to the two steps of the sealing surface formed in the cartridge, but also flows into the charging orifice 22 and effectively seals the same.

In view of the foregoing it will be appreciated that the present invention provides for the effective and efficient charging of blasting cartridges without provision of a separate valve unit for this purpose. Thus, the construction of cartridges is rendered less costly and their operation and maintenance is simplified. It is to be understood that the elements which herein serve the purposes of a valve are elements which are normally essential to the operation of this type of cartridge even though a separate valve be provided. It should also be understood that the deformable gasket is not an additional part peculiar to the present construction but is one which is normally used in cartridge construction prior to the present device. In practice, it has usually been necessary to provide a new gasket each time a cartridge is recharged and this of course holds true with the present construction.

I claim:

1. A blasting cartridge comprising a rigid casing having an opening therein, stepped sealing surfaces surrounding said opening, a closure for said opening, a gasket interposed between said closure and said stepped surfaces, means for forcing said closure and gasket toward said stepped surfaces to successively seal the closure on the respective surfaces and a passage for introducing gas into the cartridge beneath the closure when the closure is sealed against the first of said stepped surfaces, said closure and gasket serv-

ing to seal said passage when in engagement with the second of said stepped surfaces.

2. A blasting cartridge comprising a rigid casing having an opening therein, stepped sealing surfaces surrounding said opening, a rigid closure for said opening, a deformable gasket interposed between said closure and said sealing surfaces, a charging port leading from the second of said sealing surfaces to the exterior of the casing, and means for forcing said closure and gasket toward said stepped surfaces to successively seal thereon. 70 75

3. A blasting cartridge comprising a rigid casing having a discharge opening therein, stepped sealing surfaces surrounding said opening, a rupturable disc adapted to close said opening, a deformable gasket interposed between said disc and said stepped surfaces, a charging passage leading from one of said stepped surfaces to the exterior of said casing and means for forcing said disc and gasket toward said stepped surfaces to successively seal thereon, said charging passage being in communication with the interior of said casing when said disc and gasket are sealed on one of said surfaces and being effectively obstructed and out of communication with the interior of said casing when said gasket is deformed to seal on another of said surfaces. 80 85 90

4. A blasting cartridge comprising a rigid casing having a discharge opening therein, a closure for said opening, means for exerting pressure on said closure to effect an initial sealed relation between the same and said casing, a gas passage having communication 100 with the interior of said casing when the closure is so sealed, said closure being movable in response to additional pressure exerted thereon by said means to seal said gas passage 105 as well as said opening.

5. A rigid casing having an opening surrounded by stepped sealing surfaces, a closure, a deformable gasket interposed between said closure and said sealing surfaces and adapted to successively engage said surfaces in response to pressure exerted thereon by said closure, said casing having a fluid passage extending from one of said stepped surfaces to the exterior thereof and means associated with said casing for exerting pressure 110 115 on said closure.

Signed at Chicago, Illinois this 19th day of November, 1929.
